(57) **CLAIM**

The ornamental design for an inflatable pad, as shown and described.

DESCRIPTION

FIG. 1 is a first embodiment front perspective view of our new design for an inflatable pad;

FIG. 2 is a top view thereof;

FIG. 3 is a front view thereof;

FIG. 4 is a left side view thereof, the right side view being a mirror image; and

FIG. 5 is a bottom view thereof.

FIG. 6 is a second embodiment front perspective view of our new design for an inflatable pad;

FIG. 7 is a top view thereof;

FIG. 8 is a front view thereof;

FIG. 9 is a left side view thereof, the right side view being a mirror image; and

FIG. 10 is a bottom view thereof.

FIG. 11 is a third embodiment front perspective view of our new design for an inflatable pad;

FIG. 12 is a top view thereof;

FIG. 13 is a front view thereof;

FIG. 14 is a left side view thereof, the right side view being a mirror image; and

FIG. 15 is a bottom view thereof.

FIG. 16 is a fourth embodiment front perspective view of our new design for an inflatable pad;

FIG. 17 is a top view thereof;

FIG. 18 is a front view thereof;

FIG. 19 is a left side view thereof, the right side view being a mirror image; and

FIG. 20 is a bottom view thereof.

FIG. 21 is a fifth embodiment front perspective view of our new design for an inflatable pad;

FIG. 22 is a top view thereof;

FIG. 23 is a front view thereof;

FIG. 24 is a left side view thereof, the right side view being a mirror image; and

FIG. 25 is a bottom view thereof.

FIG. 26 is a sixth embodiment front perspective view of our new design for an inflatable pad;

FIG. 27 is a top view thereof;

FIG. 28 is a front view thereof;

FIG. 29 is a left side view thereof, the right side view being a mirror image; and,

FIG. 30 is a bottom view thereof.

The broken lines depict portions of the inflatable pad that form no part of the claimed design.
